S. S. HOWELL

CENTRIFUGAL SEPARATOR

Filed June 12, 1920

UNITED STATES PATENT OFFICE.

SYLVESTER S. HOWELL, OF CHICAGO, ILLINOIS, ASSIGNOR TO UNITED CHEMICAL AND ORGANIC PRODUCTS COMPANY, OF CHICAGO, ILLINOIS, A CORPORATION OF DELAWARE.

CENTRIFUGAL SEPARATOR.

Application filed June 12, 1920. Serial No. 388,674.

To all whom it may concern:

Be it known that I, SYLVESTER S. HOWELL, a citizen of the United States, residing at Chicago, in the county of Cook and State of Illinois, have invented certain new and useful Improvements in Centrifugal Separators, of which the following is a specification:

The invention relates to centrifugal separators.

One of the objects is to provide a new and improved form of separators.

Another object is to provide a separator in which the material for separation is conveyed thereinto through the open bottom thereof.

Another object is to provide an improved means for removing the more or less solid residue from the substantially vertical filtering wall of the centrifugal rotor.

Another object is to provide a device of the character described in which substances may be cooked while undergoing the process of separation.

Other, further and more specific objects of the invention will become readily apparent to persons skilled in the art from a consideration of the following description, when taken in conjunction with the drawings, wherein:

Fig. 1 shows a plan view of the form of separator shown in Fig. 2, preferably made of wood.

Fig. 2 is a central vertical section of the separator shown in Fig. 1.

Fig. 3 shows the form of device when made of sheet metal, preserving the same principles of operation.

In all the views the same reference characters are employed to indicate similar parts.

The art of separating liquid from more solid matter with which it may be associated, by the operation of centrifugal effect, broadly considered, is old, but the arrangement of introducing the material to be separated and the removal of the solid matter or residue through the open bottom of the rotating cylinder, or rotor, is believed to be new.

In this form of rotor, or rotatable cylindrical container, the residue, or solid matter from which the liquid has been extracted, may conveniently be removed through the open bottom while the rotor is in motion

and fresh supplies may correspondingly be introduced into the cylindrical rotor without stopping it, thus rendering the separating operation continuous. The machine is equally well adapted for "batch" operation. In the latter instance, the rotating container may be filled with the appropriate quantity of material from which its liquid content is to be expressed, and, after the extracting operation has been completed, the feeding operation having previously been suspended, the residue adhering to the peripheral walls of the rotatable container may be removed by a plow, or the like, with a suitable deflector.

The machine is adapted for use in the chemical industry where it is frequently necessary to remove the precipitate from the mother liquor, but in order to produce the desired result all of the mother liquor must be washed from the precipitate, in which case the rotor would be filled with a given quantity of the material to be handled, and as much of the mother liquor thrown off as feasible and the remaining portion of the liquor being washed out by the introduction of water, or other liquid, to produce the desired character of precipitate.

If, however, it is not desired to wash the material, the machine may be used as a continuous unit or may be maintained in continuous operation by the proper timing of the motion of the vertically movable feed pipe and the scraping off tool or plow, which should be maintained in lines parallel, or approximately parallel to the center or axis of the machine, by having the feed nozzles delivering material to the filtering wall in the rotating member, at different points on the inside periphery of the rotor at any given instance. Thus, when the feed pipe is discharging at the top of the filtering wall of the rotor, the scraping off tool, or plow, is working at the bottom of the wall. The feed pipe may be operated automatically, up and down, as shown, in coincidence with the plow, but in alternate relation therewith so that there will be at the center of travel of these two devices, a coincidence of feed and scraping, the effect of which is, for practical purposes, offset by having the feed pipe and the scraper as nearly together as possible so that the rotor will make practically one revolution after receiving a deposit of feed from

the pipe before the plow encounters it for the purpose of removing it.

In the drawings, the rotating container, or cylindrical rotor 5, in the forms shown in Figs. 1 and 2, is made up of a series of joined together staves 6 with intervening battens or splines 7, to break the joints and to make the cylinder substantially water tight. A head 8 is secured in the upper end 10 of the cylinder supported by a ring 9. A spider 10 is secured to the head by bolts 11 and to the cylindrical portion by bolts 12. A shaft 13, having bearings 14 and 15, is secured to the center of the spider for the 15 purpose of rotating the rotor or container 5. Hoops 16, 17 and 18 surround the cylinder to hold the staves in place. In the lower end 20 of the cylinder is a ring 19, similar to the ring 9, leaving an open space 20 in the bottom wall or ring of the cylinder. At circumferential intervals, a series of flutes or 25 tapered grooves 21, are made on the inner surface of the staves and, these are connected together by an annular groove 22. A series 30 of discharge pipes 23 are arranged in the wall of the cylinder and project therebeyond. In this particular instance there are four such pipes. They enter the groove 22 so that they are in communication with all 35 of the tapered vertical flutes or grooves 21. A reticulated inner lining filter wall 24 is bound to the inner wall of the rotating cylinder, being held in place by snap rings 25. The snap rings tend to hold the filtering 40 lining in place while the machine is at rest, the centrifugal effect serving for the purpose when the machine is in operation. A circular trough 26 surrounds the rotor and is provided with a drain pipe 27. Into this trough 45 the pipe or tube 23 from the rotor 5 projects. A belt 28 is one means by which the rotor may be driven.

The material from which the liquid is to be separated comes in through the supply 45 pipe 29 and the hose 30. This pipe is supported in bearings 31 and 32' and is vertically movable therein. The pipe is provided with a nozzle 32 on its upper end directed 50 towards the foraminous lining 24, but not in contact therewith. A pipe 33 is provided on its end with a nozzle 34. Air, under pressure, passes through the hose 35 into the pipe 33 and is projected forcibly from the nozzle 34, which points, preferably, towards 55 the filtering lining 24 in a direction opposite to the direction of its rotation as shown by the arrows so that the air will forcibly remove the residue 36 which will accumulate on the lining 24 during the process of separation. In order that the process may be 60 continuous, it is advantageous to have the nozzle 32 move axially of the machine, in the operation of depositing the material upon the reticulated lining 24, and to have 65 the nozzle 34 move coincidently therewith,

but in opposite direction, so that the material 36 after having the moisture expressed therefrom may be more readily removed.

It is convenient to have the vertical motion of the nozzles 32 and 34 in timed relation and to this end, I provide a shaft 37 supported on standard 38 and carrying a worm wheel 39 and a worm 40 for driving the shaft. A cam 41 is provided with a circumferential groove 42 in which a roller 43 75 from the end of the pipe 29 is received. Upon the rotation of the shaft 37 the nozzle 32 on the upper end of the pipe 29 is given a uniform vertical movement. A similar cam 43, having a groove 44 to receive the roller 45 on the lower end of the pipe 33, is placed in such a manner on the shaft 37 as to move the pipe 33 in the same manner but in alternate direction. The nozzle 34 produces a thin blade or jet of compressed air, which is discharged from the properly shaped orifice therein upon and under the surface 36 within the interior of the centrifugal rotor. By the operation of this sort of nozzle the filter cloth or foraminous lining, when such is used, is maintained quite free of material at all times, thus increasing the filtering capacity of the machine. With a mechanical scraper, in lieu of the pneumatic plow, it would not be possible to run 80 very closely to the inside surface of the cloth for fear of rupturing it and therefore the flexibility of the pneumatic plow offers advantage over the more inflexible or rigid blades that must be employed for mechanically scraping the material from the device. By directing the stream of air tangentially 85 in opposite direction to the direction of the rotation of the rotor, the relative velocity of the outgoing air from the jet and the material to be removed is considerably augmented.

In Fig. 3 I have shown a modified construction embodying all of the principles of operation of the device just described differing only in the fact that it is conveniently made of sheet metal.

In the former instance, as in Fig. 2, the device is especially advantageous where acids or other corrosive liquors are being handled or where, in the cooking process the use of metal is objectionable or prohibited. While the device shown in Fig. 3 might be so constructed that it would advantageously handle similar corrosive liquids, but in this event all of the parts exposed to the action of such liquids would necessarily require to be covered with hard rubber, lead or other materials more or less immune from the destructive effect of such liquids.

In Fig. 3 the vertical wall 5' is foraminous or perforated, at suitable intervals, and there is a filtering lining 24', consisting of a filter cloth made of wool or camel's hair, which forms the filter and thru which the

liquid must pass on its way to the trough or circular receptacle 26. In Fig. 3, the vertical casing 26' extends to the top because of the fact that the extruded liquid will be projected from the entire vertical, perforated wall of the rotor and, therefore wall 26' is extended above the perforated wall of the rotor in order to catch the liquid that will be projected therefrom.

10 While I have herein shown a preferred form of my invention and one modification to indicate the character of variation when the device is made of a different material, it will be manifest, to persons skilled in the 15 art, that many changes may be made in the configuration and disposition of the parts, within the scope of the appended claims.

Having described my invention what I claim as new and desire to secure by Letters 20 Patent is:—

1. A centrifugal separator comprising a cylinder having a filtering side wall against which the material is held by centrifugal action and having an open bottom thru 25 which the material is free to fall when the rotation of the cylinder is stopped; an axially movable nozzle for projecting the material against the filtering side wall when the cylinder is being rotated and a means axially 30 movable in alternate timed relation with the nozzle to loosen the material from the side wall.

2. In a centrifugal separator rotatable to filter material, a nozzle arranged to direct 35 a blast of air, under pressure, against the interior surface of the material residue to remove it from the cylinder.

3. In a centrifugal separator rotatable to filter material, a nozzle to direct a blast of air under pressure against the material residue to remove it from the separator, said air moving in a direction opposite to the direction of the rotary movement of said residue. 40

4. A centrifugal separator comprising a cylinder having a filtering side wall, closed 45 at its top end and open at its bottom end; means to rotate it on a substantially vertical axis; means to deliver material to the side wall of the cylinder and means to remove the residue therefrom, both said means passing 50 into the cylinder thru the open bottom.

5. A centrifugal separator comprising a cylinder having a filtering side wall, closed 55 at its top end and open at its bottom end; means to rotate it on a substantially vertical axis; a vertically movable nozzle operable thru the open end of the cylinder to deliver material to the side wall; a vertically movable 60 disengaging means operable thru the open end to remove the material from the filtering walls and automatic means to move the nozzle and disengaging means in timed relation.

6. A centrifugal separator comprising a 65 rotatable cylinder having filtering side walls and open at its bottom end; a non-rotatable pipe extending into the cylinder, through its open bottom end to feed material to the rotating side walls and means for relatively moving the cylinder and pipe in a vertical 70 path.

In testimony whereof I hereunto subscribed my name.

SYLVESTER S. HOWELL.
